CLAIM

The ornamental design for a display screen or portion thereof with a graphical user interface, as shown and described.

DESCRIPTION

FIG. 1 is a front view of a display screen or portion thereof with a graphical user interface (e.g., a graphical icon), showing our new design, according to a first embodiment; and,

FIG. 2 is a front view of a display screen or portion thereof with a graphical user interface, showing our new design, according to a second embodiment.

The broken lines illustrate the display screen and form no part of the claimed design.

1 Claim, 2 Drawing Sheets
